UNITED STATES PATENT OFFICE.

FREDERICK J. YANDLE, OF BELOIT, WISCONSIN, ASSIGNOR TO THE MCCORMICK HARVESTING MACHINE COMPANY, OF CHICAGO, ILLINOIS.

GRAIN-BINDER.

SPECIFICATION forming part of Letters Patent No. 257,806, dated May 9, 1882.

Application filed October 20, 1881. (Model.)

To all whom it may concern:

Be it known that I, FREDERICK J. YANDLE, of Beloit, in the county of Rock and State of Wisconsin, have invented new and useful Improvements in Grain-Binders, of which the following is a specification.

My invention relates particularly to that class of automatic binding-machines in which cord is used as the binding material, although it may to some extent prove beneficial in certain styles of wire binders; and it consists in the combination, with the knotter or tying-bill and underlying cord-guide, of a holder beneath the cord-guide adapted to receive the ends of the band and carry them along the guide until they come in position for the action of the knotter; in the combination, with the knotter, of a holder adapted to move there-toward to render up slack in the knotting operation, and a support between said knotter and holder to resist the lateral thrust of the band ends and preserve them in practically uniform relations to the knotter; in the combination, with the knotter, underlying cord-guide, and holder beneath said cord-guide, of a cutter moving transversely to sever the cord, held tense between the guide and holder; in the combination, with the knotter, of an underlying cord-guide, a holder beneath said cord-guide, a movable guide and stripper on the other side of the knotter, and a knife attached to said movable guide and stripper in position to be drawn by its movement across the cord between the guide and holder to sever it, and in other combinations and details of construction, hereinafter pointed out.

In the drawings, Figure 1 is a front elevation of a binding-head embodying my improvement. Fig. 2 is a top plan view thereof; Fig. 3, a side elevation, illustrating the action of the holder; Fig. 4, a detached view of the cord-guide, and Fig. 5 a detached view of the movable guide and stripper.

A is the stock of the binding-head, and B a knotter, of the type known as "tying-bills," supported therein. The axis of this knotter in the present instance is shown as horizontal, or substantially so; but it will be obvious from the ensuing description that it may assume

any desired inclination, provided the relation of the other parts thereto is maintained.

C and D are cams which control the pivoted jaw of the knotter, the latter cam operating to open it when it has partially completed a revolution, to admit the ends crossed over the loop beneath it, and the former to sharply close it upon these ends as the revolution is finished.

At a proper distance beneath the jaws is a holder, E, composed in this instance of a rotating notched disk, e, which takes into a spring-pressed shoe, e', and is intermittently moved to force the cord into said shoe, and thereby clamp it. It is desirable that the holder should yield or move up toward the knotter during the tying operation in order to render up slack. The length of the ends stretched between knotter and holder at the moment of the initial movement of the former will in such case often be so great as to cause a very considerable liability to escape from the action of said knotter when it once commences its revolution, since its surfaces are necessarily, to some extent, cam-shaped. Moreover, whether the holder is movable or stationary, this tendency usually, to some extent, exists, as there must be a certain space at all times between it and the knotter or band-securing device. I therefore arrange between the knotter and holder a curved deflecting or guiding arm, F, attached firmly to the stock by a bolt or other connection, f, and directed from that side of the cord-receiving space opposed to the knotter inward and downward toward and underneath the latter, and then laterally a short distance outward, as shown. This serves to guide or lead the band ends of the cord into proper position for the initial action of the knotter, and also to resist and correct the side-wise thrust, push, or displacement given them by the latter as they slip over its crown to form the cross or twist in the loop. Upon the frame is mounted another guide-arm, G, having a guide-way, g, which, when the binding-arm is laying the cord to form the band, rests in front of the knotter and co-operates with the other guide in positioning the cord. In order that the arm G may subserve other functions, it is pivoted upon the stock and controlled at its heel end in

such manner that after the knot is formed it is swung aside and bears upon the band between the knotter and the sheaf to strip it forcibly from said knotter. A knife, g' , is also attached to this guiding and stripping arm G in such position that as it starts on its side-wise movement to strip the knot said knife is brought against the strands stretched between the other cord-guide and the holder and severs them.

In the binding-head I have chosen for illustration the inner or under jaw of the knotter is the pivoted one. The binding-arm delivers the cord to the holder through the space or opening h behind both cord-guides, and at this time the knotter is stationary, with its jaws in a substantially horizontal position transverse to this opening. When both ends of the cord have been delivered to the holder the disk e of the latter moves one notch in the direction of the arrow, carrying them into the shoe and firmly clamping them. This movement takes the ends stretched between the knotter and holder along the curved edge of the guide F and lays them under the chin of the knotter, which then commences to rotate. By the time the knotter has entered the third quarter of its revolution the loop is formed and the ends leading to the holder are crossed thereupon. The inner jaw now opens, while the nose of the outer jaw passes close above and almost in contact with the upper surface of the underlying lateral extension j'' of the guide F, completely shutting off the cord ends between the gavel and the holder from escape and causing them to be directed with certainty into and between the jaws. Just as the revolution is completed the jaws come together under the force of the cam C and seize the ends. The stripper-arm is then actuated, and as it swings aside it first draws its knife against the strands stretched tense between the guide F and the holder and severs them, the guide at this time acting as a stop against lateral movement of the strands before the knife. As the stripper-arm continues its movement the loop is drawn from the knotter and tightened upon the ends held between the jaws of the latter,

and finally these ends are wrenched from its grasp and the bound sheaf drops to the ground, 50 when the parts are restored to their initial position for the next binding operation.

I claim—

1. In combination with the knotter or band-securing device, an underlying cord-guide and a holder beneath the cord-guide adapted to receive the ends of the band and carry them along the guide until they come in position for the action of the band-securing device. 55

2. In combination with the knotter or tying-bill, a holder adapted to move theretoward to render up slack in the knotting operation and a support between said knotter and holder arranged to resist the lateral thrust of the band ends. 60

3. In combination with the knotter or tying-bill, an underlying cord-guide and a holder beneath said guide adapted to move toward the knotter during the tying operation to render up slack. 70

4. In combination with the knotter, underlying cord-guide, and holder beneath said cord-guide, a cutter moving transversely between the guide and holder to sever the cord ends. 75

5. In combination with the knotter, an underlying cord-guide, a holder beneath said cord-guide, a movable guide and stripper on the other side of the knotter, and a cutter attached to said guide and stripper in position to be drawn by its movement across the cord between the first-named guide and holder to sever it. 80

6. In combination with the tying-bill having pivoted inner jaw, a cord-guide formed and arranged as described, whereby the nose of the fixed jaw is caused to traverse a part of said guide as it approaches the end of its revolution and while the pivoted jaw is open. 85

7. The cord-guide F, having the outline shown and described, and arranged substantially as set forth. 90

FREDERICK J. YANDLE.
